(57) CLAIM

The ornamental design for a stand for an oil lamp, as shown.

DESCRIPTION

FIG. 1 is a perspective view of a stand for an oil lamp, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is top plan view thereof;

FIG. 7 is a bottom plan view thereof; and,

FIG. 8 is a perspective view thereof, showing an oil lamp mounted in the top in broken lines which are for illustrative purposes only and forming no part of the claimed design.
